SWING

Carl L. Hannas, Fort Kent, Alberta, Canada

Application May 16, 1952, Serial No. 288,147

2 Claims. (Cl. 155—62)

1

This invention relates to new and useful improvements in a "teeter swing" and more particularly to a teeter swing of the type which is operated by the occupants pushing against the back-rest of seats provided on each end of a pivotably suspended platform.

The teeter swing embodies a supporting structure having two upright members. A platform is pivotably suspended from the upright members at a point on each substantially below the upper end thereof. The platform is free to pivot about these points. At least one seat is provided at each end of the platform. Each of these seats has leg members which are pivotably mounted at the lower ends thereof to the platform. If only one seat is provided at each end of the platform, each of the leg members associated therewith is pivotably connected near its upper end to one end of a connecting member. The other end of each connecting member is pivotably connected to one of the upright members at a point substantially above the point of platform suspension. If second seats are provided, they are connected to the first seats.

The term "platform" is used to refer to any substantially rigid structure extending from one seat to the other of which a part near each seat is suitable to be stepped upon by a person using the swing.

The invention will be more fully understood by reference to the following detailed description taken in conjunction with the attached drawings wherein:

Figure 1 is a perspective view of the teeter swing,

Figure 2 is an enlarged perspective view of the suspension pivot for the platform,

Figure 3 is a perspective view of one end of a seat as shown in Figure 1, and Figure 4 is an enlarged detail view of part of the platform of the swing shown in Figure 1.

The supporting structure comprises horizontal foot members 10 and upright members 11. The upright members 11 may be bolted to the foot members 10 as at 12. The upright members 11 and foot members 10 may be braced for greater rigidity as with diagonal members 13, cross-bracing members 14 and members 15, 16, 17, 18. It will be understood that any of the members 13, 14, 15, 16, 17 or 18 may be of angle section or any other cross-section which will impart rigidity to the supporting structure.

A platform 19 is pivotably suspended from the upright members 11 at 20 through supporting members 21 and gusset plates 22.

2

One of the pivotable suspensions 20 is shown in greater detail in Figure 2, and consists of a Z-shaped member 24 bolted to one of the upright members 11, an inverted T-shaped member 25 to which is bolted the supporting members 21, and a pivot 26 extending through the upright member 11, the inverted T-shaped member 25, and the Z-shaped member 24. The T-shaped member, and hence the platform depending therefrom, is pivotable about the pivot 26. In order to more fully support the ends of the platform 19, supporting members may be provided as shown at 27. Cross members 45 are welded to each end of the platform 19. The cross members 45 extend past the edges of the platform 19, and the supporting members 27 are welded to the ends of the cross members 45 so that the members 27 are spaced from the edges of the platform 19. The cross members 45 are each formed of a pair of angle irons joined at their ends. An angle iron member 46 is welded to each cross member 45 and has welded to it pivots 47 (see Figure 4).

At each end of the platform 19 is a seat 28 which has leg members 29. The lower end of the leg members 29 is pivotably connected to the platform 19 as at 30 (Figures 1 and 3). A connecting member 31 is pivotably connected to each of said leg members 29 near the upper end thereof at 32 (Figures 1 and 3) and to one of the upright members 11 at 33. Each of the seats 28 is provided with a back-rest 34 and a foot-rest 35 which if desired may be pivotable for greater foot comfort. The foot rests 35 are formed of angle irons running across the platform 19 and welded to uprights as shown in Figure 1. The pivoted connections 30, 32, 33, 38, 40 and 41 are each constructed of a pin welded in the angle of an angle iron and a boxing of conventional form arranged to bear on the pin. This construction for pivoted connection 30 is shown in Figures 3 and 4 in detail and a similar construction is used for the other pivoted connections.

The occupants of the swing seat themselves in seats 28 with their backs against the back-rests 34 and their feet on foot-rests 35. To operate the teeter swing the occupants in one of the seats 28 (say the right-hand one) relax while the occupants of the other seat 28 (the left-hand one) push with their backs against the back-rest 34 and their feet against the foot-rest 35. This causes the platform 19 to begin to rotate about the pivot 26 in a clockwise direction; that is, the left-hand end of the platform 19 goes up whereas the right-hand end goes down. When the right-hand end of the platform approaches the ground,

the occupants of the left-hand seat 28 should relax whereas the occupants of the right-hand seat 28 should push against the back-rest 34 as was done initially by the left-hand seat occupants. This will cause the rotation to reverse. In other words, the platform 19 will assume a counter-clockwise rotation until the left-hand seat 28 approaches the ground, at which time the rotation will again be reversed.

If desired, a second seat 36 may be provided at each end of the platform 19 in front of the seat 28. Each of these seats 36 has leg members 37, the lower ends thereof being pivotably attached to the platform 19 as at 38. A member 39 connects each leg member 37 to the leg member 29 immediately therebehind through pivots 40 and 41. Associated with each seat 36 is a foot-rest 42 similar to the foot-rests 35, and a back-rest 44 similar to the back-rest 34. Thus, occupants of the seats 36 perform the same function as occupants of the seats 28. A U-shaped opening in each of the back-rests 44 may be provided to give easy access to the seats 28.

It will be understood that the supporting members 27, the connecting members 31, and the members 39 may be of angle section or any other cross-section which will impart rigidity.

The platform 19 may be provided with a corrugated floor, as shown in Figure 1 so that one may walk up or down the platform without slipping when it is in an inclined position. The corrugated floor may be formed of narrow wooden planks, each bias cut so that two planks fitted together form one corrugation.

What I claim as my invention is:

1. A teeter swing comprising a supporting structure having upright members, a platform pivotably suspended from said upright members and having a seat at each end thereof, each of said seats having leg members pivotably attached at their lower ends to said platform, and a connecting member associated with each leg member having one end pivotably attached thereto near the upper end thereof, each of said connecting members having its other end pivotably connected to one of said upright members at a point above the point of platform suspension.
- 15 2. A teeter swing as claimed in claim 1, wherein a second seat is provided towards each end of said platform in front of said first seat, each of said second seats having leg members pivotably attached at their lower ends to said platform and pivotably attached at intermediate points to the adjacent leg members of the adjacent first seat.
